UNITED STATES PATENT OFFICE

2,437,058

COLLAPSIBLE CONTAINER FOR AIR
TRANSPORTATION OF FLUIDS

Harry F. Waters, New York, N. Y.

Application July 3, 1943, Serial No. 493,340

3 Claims. (Cl. 150—0.5)

1

This invention relates to improvements in methods of transporting liquids, and more particularly volatile liquids, such as aviation gasoline, and to improved collapsible containers and means for installing and maintaining same in aircraft, as well as in land vehicles.

In the present day development of aerial traffic, and, more particularly, with reference to the astounding and critical development of air transport for war materials, and particularly for aviation gasoline, it has become necessary to develop ways and means to permit the packaging and transport of aviation gasoline and other products.

Fuels are now improving and the preferred composition is 100% octane gas, comprising 60% of the total mix, plus 40% aromatics. This fuel combination has a much lower boiling point than any of the fuels utilized heretofore. When using such fuels, and with the sudden ascent of a plane, it becomes of extreme importance to quickly equalize pressures in the fuel system, in order to keep the gasoline tanks from having terrific pressures exerted therein or thereupon (ascent and descent). As airplane type engines are coming more into use as power plants for automobiles, tanks, tractors and heavy equipment, generally, this type of fuel will have an increasingly widespread use. Consequently, the low boiling points of these fuels will necessitate some method of utilizing the gaseous vapors, even under normal conditions of operation.

Metallic containers, generally, have proven to be unsuited for aerial transport of vaporous liquids. Among the difficulties attendant upon the use of metal containers are the following: Fixed character of the container, requiring its disposal at the end of a trip, or its return as non-pay-load with the consequent exclusion of pay-load; tendency of the vaporous contents to boil or distil off when subjected to high heat or to rarefied atmospheric conditions obtaining in high altitude flights; the liberation of vapor is particularly critical in desert areas where heat-engendered pressures in wing tanks of aircraft have been known to buckle and deform the wing surfaces. Other disabilities attendant upon the use of metal containers are the excessive weight of the containers per unit of gasoline delivered, as well as the inability to stow or pack cylindrical or barrel containers so that a maximum of available cargo space can be utilized.

It has now been found that relatively light-weight, liquid-tight, collapsible containers, can be prepared and mounted in aircraft to permit

2

of the transportation of a maximum pay-load of aviation gasoline, with the collapse of the containers at the discharge of the contents, and the utilization of the freed cargo space for maximum pay-load return trip. It has also been found that by connecting the containers to the engine fuel-supply system, a better distribution of the fuel load can be obtained, and the wing space freed for gun installations and other material of non-varying weight and/or volume. In addition, it has been found, and the present invention contemplates the withdrawal of evolved vapors from the fuel tanks or containers into the engine fuel supply, thereby avoiding discharge of highly flammable vapors into the slip-stream of an aircraft, where it would be in imminent danger of ignition from the motor exhaust. This utilization of normally dissipated fuel vapors increases the efficiency of the aircraft as a transportation agency for volatile fuels, because of the fact that any loss in pay-load is compensated for by the use of the loss as direct motor fuel.

It is to be understood that parts of this fuel system, even without the collapsible tank, may be of extreme value in the future and the scope of this invention is not limited to the use of this system in conjunction with collapsible tanks.

The present invention, therefore, envisages and proposes the use of special, collapsible, light-weight containers, for transport of liquids and particularly liquid fuels having a high percentage of vaporous constituents, in standard aircraft, and the elimination of fire hazard by the diversion or controlled direction of any evolved gases or vapors into the fuel system of the aircraft, instead of venting same into the slip-stream.

Some of these tanks can thus be utilized with auxiliary tanks for extended trips without requiring any alterations in existing fuel installations and without requiring transfer of fuel from one container into a stationary fuel tank during the course of a trip or flight.

The above, and other desirable features and advantages of the present invention will be described in the specification, and illustrated in the accompanying drawings, certain preferred embodiments being shown by way of example only, for, since the underlying principles may be incorporated in other specific structures and assemblies, it is not intended to be limited to the ones here shown, except as such limitations are clearly imposed by the appended claims.

In the drawings, like numerals refer to similar parts throughout the several views, of which

Fig. 1 is an elevation of a collapsible container in erected form;

Fig. 2 is an end elevation of the container of Fig. 1 showing the manner of lacing the cover in place;

Fig. 3 is a vertical section taken on line 3—3 of Fig. 1;

Fig. 4 is a vertical section taken on line 4—4 of Fig. 2;

Fig. 5 is an enlarged detail of a corner binding 10 tape;

Fig. 6 is a vertical section of a container closure and cap, showing the method of securing the same to the bladder and casing;

Fig. 7 is a plan view of a portion of a collapsed 15 container and bladder;

Fig. 8 is an elevation of an end-supporting panel;

Fig. 9 is an end elevation of a pair of erected containers as mounted on cradles or stands;

Fig. 10 is a top plan view of the mounted and secured containers of Fig. 9;

Fig. 11 is an elevation of an aeroplane, partly in broken section, showing the installation therein of collapsible fuel containers;

Fig. 12 is a plan view of the interior of a fuselage showing a frame work for receiving collapsible containers;

Fig. 13 is a vertical section taken on line 13—13 of Fig. 12;

Fig. 14 is a view similar to Fig. 13, showing the liquid containers collapsed and retracted and the freed space filled with cargo, and

Fig. 15 is an elevation of a pair of mounted containers with main feed lines and vapor lines 35 connected to a motor fuel supply.

Referring now to Figs. 1 to 8, there is shown a container comprising a bladder or envelope 10 disposed in a casing 20. The envelope or bladder 10 may comprise a pair of mating sheets 11 of 40 liquid-resistant material, such as fabric impregnated with plastics, including rubber substitutes, or vinyl resin compounds and derivatives, sulphur resins, and other materials which are susceptible of being heat-sealed or vulcanized. These sheets are vulcanized at their mating edges, as indicated at 12, to give a liquid-tight bladder or envelope. The envelope is provided with a plurality of apertures 13 in which are inserted outlets 30, the outlets being disposed in and passing through apertures 21 formed in the container walls. The outlets 30 and their construction and installation will be described more in detail hereinafter.

The bladder 10 is inserted into the container 20, when the latter is in collapsed condition as indicated in Fig. 7. As shown in this figure, the marginal edges of the bladder are folded over to provide slip-joints 14, and an appreciable excess of stock, 15, protrudes from the ends of the container. The container 20 comprises top wall 22, bottom wall 23, front and back side walls 24, 25 and end sections 26. The top and bottom panels 22, 23 are centrally hinged, as indicated at 27. The side walls are hinged at their edges, as designated generally by the numeral 28, while the end sections are provided with edge hinges, designated generally by the numeral 29.

In the construction of the container 20, the top and bottom and front and rear walls are formed of boards or planks 40 of plywood or plain wood, 70 enclosed in heavy duck or canvas 41. The canvas or duck coverings are sewed together adjacent the edges of the boards, as shown at 42. In the construction shown herein, the front and back walls of the containers are made of individual 75

boards, while the top and bottom are made of a pair of boards, covered as indicated, the canvas covering being sewed along the seam line 21, all as indicated at 43. A plurality of heavy duck straps or tapes 44 are secured to the longitudinal faces of the container, as by stitching, 45, while a plurality of transverse belts or straps 46, secured by stitching 47, are passed around the container. The end panels, as indicated, are trapezoidal segments 26 formed as continuations or extensions of the covering fabric 41. The strap members 44 are coextensive with these flaps and overlie and are secured to the fabric 41 by the usual stitching 45. At their free edges the flaps are covered by strips or tapes 28 folded in position as indicated in Fig. 4, and extending outwardly at the corners and thereover and therealong to form the edge binding tapes for the assembly. The inner edges of flaps 26 are provided with grommets or eyelets 48 passing through the folded over edge binding tape 28 and securing same to the flap fabric 41, and associated tapes 44.

When the container 20 and associated bladder 10 are erected into squared-up position by applying pressure to the fold lines 27, the ends 15 of the bladder are folded inwardly of the container and held in place by end panels 50 conforming to the cross section of the container. The flaps 26 are brought over the inserted panels 50, and laced together by lacings 51 secured by knots 52, all as shown in Figs. 1 and 2. Here it will be seen the lacings are passed through eyelets of opposed tabs in the same manner as the lacing up of a shoe, and then tied securely. This lacing serves to taunt the flaps 26 and clamp the walls down on the end panels 50 in gripping engagement from all sides. The erected container is then ready to receive its cargo or load of aviation gasoline, or the like, which is introduced through the filling or discharge nozzle 30.

The construction of the filling spout or discharge nozzle is as follows. The members 30 comprise a main body or pipe section 31, having a bottom everted flange 32, with concentric ridges 33, 34 on the top side thereof. Standard threads 35, 36 are provided on the inside and outside surfaces of the pipe or body section 31. A threaded filler cap 37 having a gasket 38 may be screwed into the threads 35. A pair of screw-threaded clamping rings 39a, 39b complete the assembly. As shown in Fig. 6, the spout or nozzle 30 is fitted in through aperture 13 of bladder 11 with the ridges 33, 34 in contact with the inner surface of the bladder. It will be noted that the bottom flange 32 extends beyond the aperture 21 to a point well within the enclosing board or container section 40. With the nozzle 31 in place, clamping ring 39a may be screwed down in place on thread 36 by means of a spanner wrench, so as to cause ridge 33 to bite into and engage its contacting section of bladder 11 which is held in place by the clamping ring. It is to be noted that this clamping ring fits within the aperture 21 in the wall of container 20, and is nested therein. A second enlarged clamping ring 39b is then screwed down on the threaded outlet, the dimensions of this member being such that its outer edge or rim overhangs the edge or rim 34 of flange 32. Upon screwing up clamping ring 39b, the section of container 20 thereunder is clamped and ridge or annulus 34 is forced into the surface of bladder or liner 11. Thus it will be seen that the liner of bladder 11 is doubly gripped by and between the ridges or rings 33, 34, and the cooperating locking nuts 39a and container section 40 and

its cooperating locking nuts 39b. Upon screwing down of standard threaded filler cap 37, the assembly is complete.

Referring now to Figs. 9 and 10, the erected containers 20 may be mounted in cradles 60 for transportation. These cradles may comprise an outer course of planks 61, 2 x 10 inches, and an inner abutting course 62 of 2" x 4" stock. The containers are adapted to sit on the rails formed by members 62 fitting snugly within the space formed by members 61. A plurality of staples or securing members 63 are provided around the periphery of members 60, and these serve to receive and hold securing straps or rods 64 having sections 65 in engagement therewith, and being provided with tightening devices 66 to permit the clamping down of the containers into seated, nested engagement in the cradle 60. With such a construction, it will be seen that the containers 20 will be rigidly held against all shifting during transport, and will be normally safe and secure.

While the method of securing described immediately above is generally applicable to all types of transportation vehicles, certain special problems are presented when aircraft are to serve as the transportation media.

Turning now to Figs. 11 to 15, there is shown the manner and means for installing and transporting collapsible containers loaded with high octane or aviation gasoline. In the set-up shown, an airplane 100 has the usual wings 110, nose 120, fuselage 130, and tail assembly 140. Propellers 150 and associated engines complete the assembly. As shown, the engines may be mounted in individual nacelles 160. In the fuselage 130, and aft of the front bulkhead 131, the containers may be arranged in any suitable manner. The center line of the fuselage is designated, for convenience, by the numeral 200, while the transverse equilibrium or normal load line of the plane is designated by the numeral 201. In the discussion which follows it is to be noted that all assemblies are predicated upon maintaining a proper balance forward and aft of line 201—201.

Referring more particularly to Figs. 12 and 13, it will be noted that the fuselage is developed and built around a plurality of spaced annular ribs 202, here shown as being of L-section. The mode of securing the skin of the fuselage to the supports forming no part of the present invention, details are omitted. In the cargo space at the rear of bulkhead 131, a front cross piece or stringer, 210, is stretched between a pair of ribs 202 and secured thereto by bolts and nuts designated generally by the numeral 211. This cross piece or stringer may be of 2" x 10' stock. A duplicate stringer assembly is formed at the rear end of the cargo space. Intermediate the end stringers 210, are provided pairs of cross pieces 215 of similar construction, extending from and secured to opposed hangers 220. The hangers 220 are secured to supports 221, 222, 223, each of which is fastened to an associated rib 202 by the usual bolt and nut construction 211.

Individual cradles or container supports are built in the manner similar to that shown in Fig. 9 for individual containers. The container supports are designated 60 for purposes of convenience. In the installation shown in Figs. 12 to 15, the stringers 61 and 62 are mounted on and between the cross beams or stringers 210, 215. A plurality of intermediate braces 67 may be disposed between and secured to the framing members 62, being secured thereto in any suit-

able manner, not shown. A cat-walk or planking 68 may overlie the central framing members 61 and be secured thereto in the usual manner. With this arrangement the platforms or container beds 60 are suspended in the fuselage and across the ribs thereof, and the plurality of container beds is so arranged that the load can be evenly distributed in the fuselage and the stresses supported uniformly from the framing members of the aircraft.

With the containers 20 set in their respective ports or wells, the load is firmly supported, and with the tie-downs 64, absolute rigidity and non-shifting during flight is assured.

When the containers 20 have been discharged of their contents, they may be collapsed or folded inwardly as described hereinabove, and moved over and secured to the side of the fuselage as indicated in Fig. 14. The remainder of the cargo space thus freed may be filled with packages or goods of any suitable description, and designated generally by the numeral 69. It will be noted that due to the absence of round drums or containers, maximum cargo space is utilized in the shipment of aviation gasoline and the like, and that the containers therefor, when discharged, can be returned without occupying any measurable cargo space, the cargo space thus freed being available for return pay-loads, as indicated. Owing to the weight of gasoline cargoes, the return pay-load in crude drugs, medicinals, ores, ingots, rubber, and other critical materials, may be worth many times that of the gasoline handled, yet which materials could not hitherto have been transported on return trips due to the lack of available cargo space.

As intimated hereinabove, the improvements of the present invention provide special safety factors in the transport of flammable, vaporous liquids, and assure the delivery of maximum payloads, due to the fact that none of the transported material is jettisoned, or vented to the atmosphere, without having first been directed through the fuel lines of the engines. This highly important and novel feature will be more clearly appreciated by reference to Figs. 11 and 15, wherein the details of such a system are shown. Where the safety system is incorporated in an airplane or other carrier, the containers 20 are severally provided with bottom discharge valves 70, top gas outlet valves 71, and inlet check valves 72, all of which are so constructed and installed as to prevent loss of fuel during looping of the plane in flight. Dumping valves not shown, may also be included in the tank assemblies, for emergency use. The valves 70 are tapped into a common pipe or header 73 provided with a check valve 74, and connected to a motor feed line 75, which is connected to the carburetor 76 of any suitable motor. The vapor discharged through gas outlet valves 71, is fed into a gas line 80, having an outlet safety valve 81, and connected through an intake check valve 82 to a manifold 83 of an engine. Where a plurality of engines constitutes the power plant of an aircraft, the fuel lines and gas lines will be evenly distributed between them. If, for any reason, the discharge of vapor through line 80 is not utilized, as by chilling of the contents of fuel tanks 20, with shrinkage in volume, any air necessary for maintaining equilibrium in the system will be aspirated in and through the inlet check valves 72. The several fuel valves, gas outlet valves, and check valves can be calibrated and set for the most efficient operation of the

power plant, and to insure the positive withdrawal of any evolved vapors from the containers directly into one or more of the engine units, thereby positively eliminating any chance of the introduction of flammable vapors into the slip-stream of the aircraft.

Having now particularly described and ascertained the nature of my said invention, and in what manner the same is to be performed, I declare that what I claim is:

1. A flat-foldable collapsible fuel container for aircraft, comprising an inner, inflatable, liquid-tight envelope, a fabric covering for the envelope secured thereto in predetermined areas, rectangular stiffening members in the sides of the cover, end flaps at the ends of the cover and adapted to receive and retain rectangular end-forming panels, means for adjustably securing the end flaps together, and at least one outlet or filling member secured to the envelope and the cover, effective to cause the envelope to be erected from flat, collapsed condition, into rectangular shape with the cover.

2. A flat-foldable collapsible fuel container for aircraft, comprising an inner, inflatable, liquid-tight envelope, a fabric covering for the envelope secured thereto in predetermined areas, the said envelope when expanded having greater cubical capacity than the covering, rectangular stiffening members in the sides of the cover, end flaps at the ends of the cover and adapted to receive and retain rectangular end forming panels, means for adjustably securing the end flaps together, the securing means comprising at least one outlet or filling member secured to the envelope and the cover, whereby to cause the envelope to be erected from flat-folded, collapsed

condition into rectangular shape with the cover.

3. A flat-foldable cover for collapsible liquid containers, comprising longitudinal panel sections of fabric, rectangular stiffening inserts within the sections, at least two opposed sections being bipartite and all of the sections being joined by hinge lines, and separate end sections comprising trapezoidal segments secured to the ends of the panel sections and having their free ends covered with binding tape, the said tape extending along the longitudinal edges of the cover and being secured thereto.

HARRY F. WATERS.
